UNITED STATES PATENT OFFICE

2,245,686

LAMP GUARD

Francis C. Kollath, Chicago, Ill.

Application June 16, 1939, Serial No. 279,466

1 Claim. (Cl. 240—102)

This invention relates to lamp guards and particularly to lamp guards which are removably connected to a portable handle.

An important object of the invention is the provision of a lamp guard having a reflector or shade mounted within a guard, there being means operable from without the guard to shift the position of the reflector or shade to any desired position.

Another object is the provision of a lamp guard having a reflector or shade arranged interiorly thereof, including means to permit the shade or reflector to be shifted to various positions and then locked in the adjusted or shifted position.

A further object of the invention is the provision of a lamp guard having a hook for hanging the guard, as well as a reflector arranged inside of the guard and shiftable by means of a rotatably mounted element, or by connecting the hook directly to the shade or reflector so that the reflector can be positioned inside of the guard at any place desired.

A still further object of the invention is the provision of a lamp guard of the type having a split collar so that the same may be spread apart for ready insertion of the lamp globe, there being novel means for selectively shifting the shade or reflector to various positions and then locking the shade in said adjusted or shiftable position.

Another important object of the invention is the provision of a split lamp guard having parts provided with semicircular extending lips held together by a ring washer, including means for locking the parts in clamping engagement by the rotation of an element, the element including a threaded stem to permit such locking engagement, and carrying a lamp shade or reflector which is locked in adjusted position by the same means which locks the part of the guard together.

Numerous other objects and advantages will be apparent throughout the progress of the following specification.

The accompanying drawings illustrate selected embodiments of the invention, and the views therein are as follows:

Fig. 1 is an elevational view of one form of lamp guard embodying the invention;

Fig. 2 is another elevational view at right angles to that shown in Fig. 1.

Fig. 3 is a detail sectional view on the line 3—3 of Fig. 2;

Fig. 4 is a detail sectional view similar to Fig. 3, but showing the manner in which the parts may be disassembled;

Fig. 5 is a detail sectional view showing a hook

supporting the shade in combination with the locking mechanism;

Fig. 6 is a detail elevational view of another form of lamp guard embodying the invention; and

Fig. 7 is a detail vertical sectional view on the line 1—1 of Fig. 6.

Referring to the drawings, and particularly to

Figs. 1 to 5 thereof, 10 designates a lamp guard preferably made of cast metal, such as aluminum, and comprises two parts 11 and 12, the parts being divided along the line 13, there being a plurality of vertical and horizontal supports or webs 14 and 15, respectively. A split collar 16 is integrally connected to the vertical webs 14

and is provided with cooperating lugs or bosses 17 to accommodate a screw or bolt 18 to lock the two parts together. The parts 11 and 12 may

be provided with extensions or lips 19 on one

section, which are adapted to be received in

corresponding depressions 20 formed in the other

section, whereby the parts are interfitting or

interlocking connected together. The halves 11

and 12 may be provided with substantially semi-

circular ears or lugs 21 arranged to form a split

ring 22 at the upper part of the guard 10, Figs.

3 and 4, where the two semi-circular parts are

placed together. These ears 21 flare upwardly

and outwardly to provide, in effect, an annular

groove 23 to receive a locking washer or ring 24.

The guard 10 may be spread apart, Fig. 4, so as to

permit the insertion or removal of a lamp globe

or a reflector 25, or the guard may be completely

dismantled. The screws 18 are loosened and re-

moved to permit the parts 11 and 12 to be spread

apart to install or remove a lamp or shade, the

ears 21 and the washer 24 acting as a hinge

connection. Also, the outwardly flared ears 21

may be slid outwardly from underneath the

washer 24 to disjoin or uncouple the parts 11

and 12.

The shade or reflector 25, of any desired form

or configuration, is fastened to an upstanding

threaded member 26 which extends through an

opening 27, Figs. 3 and 5, formed in the upper part

of the guard at the ears or lugs 21. The shade

or reflector 25 is fastened to the member 26 in

the manner shown, such as by peening or up-

setting the lower end, as indicated at 28. A

washer element 29, Figs. 3 and 5, is arranged be-

tween the upper surface of the shade or reflector

and the underside of the guard at the top thereof

to permit free revoluble movement of the shade

inside of the guard. A lock nut 30 threadedly

engages the stem 26, and its purpose is to lock

the shade in adjusted position. The lock nut 30

is provided with a bevel portion or cone-shaped end 31 which is adapted to fit down in the seat about the opening 27 when the lock nut 30 is screwed home so as to spread the halves outwardly at the top of the guard 10, pressing the ears 21 outwardly against the ring 24 and thereby locking the two parts at the upper end in positive engagement. In order to change the position of the shade, the lock nut 30 is loosened sufficiently on the threaded stem 26 so as to permit the shade to be rotated in the guard 10 by operating a knob 32 on top of the threaded member 26, Figs. 1 to 4. The shade or reflector 25, the stem 26, the thumb nut 30, and the member 32 act as a unit. When the thumb nut 30 is loosened sufficiently, the entire unitary structure can be rotated within the guard 10, thereby adjusting the shade or reflector 25 to any desired position about the central stem 26. After the shade is arranged in adjusted position, the thumb nut 30 is then operated again to lock the parts securely in place and to hold the shade in adjusted position.

A hook 33, Figs. 1, 3 and 4, may be fastened to a part of the guard 10 to permit the guard to be hung from a support. This hook 33 may be rigidly connected to the guard, or it may be revolvably mounted, as desired. However, a hooking element may be provided, Fig. 5, by providing a hook 34 on the threaded member 26. This may be accomplished by elongating the member 26 and bending it in the form of a hook, as shown in Fig. 5, whereby the hook 34 will operate in place of the knob 32, the lock or thumb nut 30 being threadedly mounted on the threaded portion 26 which constitutes the stem portion of the hook 34.

The shade or reflector 25 may also be arranged in a different form of lamp guard, as shown in Figs. 6 and 7. In these latter figures, a guard 40 is made up of a plurality of vertical wires 41 and circular transverse or horizontal wires 42, the horizontal wires being split at opposite sides at the point indicated at 43, Fig. 6. The vertical wires 41 terminate in a bottom split collar 44 which is formed of two parts and connected together by screws 45 passing through ears 46, Fig. 7. The upper ends of the vertical wires 41 extend through holes provided in a disk 47 and are bent inwardly to locking engagement, as indicated at 48. The upper ends of the vertical wires 41 have free movement in the holes of the disk 47 to permit pivotal movement of one-half of the guard with respect to the other half. A hook 49 passes through an opening 50 formed in the center of the disk 47 and is secured to the reflector 25, as indicated at 51, Fig. 7. A washer 52 is arranged between the turned ends 48 of the wire and the upper surface of the shade or reflector 25 to permit free revoluble

movement of the shade in the guard. A lock nut 53 having a cone-shaped end threadedly engages the stem 54 of the hook 49 and bears against the disk 47. To prevent the turned ends 48 of the vertical wires from interfering with or obstructing the operation of the shade the washer 52 is interposed between the ends 48 and the top of the shade. When the lock nut 53 is tightened, the washer 52 will be forced against the ends 48 of the wires and lock the shade in adjusted position. To shift the reflector 25, the lock nut 53 is loosened sufficiently to permit the hook 49 to be rotated to move the shade to its new adjusted position. The guard 40 is shown clamped about a rubber handle 55, Figs. 6 and 7. To insert the reflector or shade within the interior of the guard, the screws 45 are loosened, and the two halves of the guard spread apart, the wires 41 pivoting in the holes in the washer element 47. The lower end of the guard is, therefore, capable of being spread apart a sufficient distance to permit the insertion of the lamp as well as the shade.

The invention comprises a shade element arranged inside of the guard and thereby being fully protected and prevented from injury. The shade or reflector can be shifted to any desirable position within the guard by merely operating a lock nut to loosen the elements and then turning a stem which is connected to the shade.

Changes may be made in the form, construction and arrangement of the parts without departing from the spirit of the invention or sacrificing any of its advantages, and the right is hereby reserved to make all such changes as fairly fall within the scope of the following claim.

The invention is hereby claimed as follows:

A two-part lamp guard adapted to be spread apart and comprising a shade or reflector element arranged interiorly thereof, a pair of upwardly and outwardly extending ears on the guard at the upper end thereof which when the two parts of the guard are together in closed position form a split collar having an outer annular groove, a washer element about the ears and arranged in the annular groove, said ears having semi-circular openings therein whereby a circular concentric opening is provided when the two parts of the guard are together in closed position, a threaded stem on the element extending through said opening and projecting above the top of the guard, and a lock-nut threadedly engaging the stem and spreading the ears outwardly against the washer and frictionally locking the element in place, said stem being adapted to be turned to shift the position of the element when the lock-nut is loosened.

FRANCIS C. KOLLATH.
